UNITED STATES PATENT OFFICE.

CHARLES M. LUNGRAN, OF BAYONNE, NEW JERSEY, ASSIGNOR TO THE SAFETY CAR HEATING & LIGHTING COMPANY, A CORPORATION OF NEW JERSEY.

STRAINER AND PERFORATE DISCHARGE FOR LAMPS.

No. 880,149.

Specification of Letters Patent.

Patented Feb. 25, 1908.

Application filed February 20, 1906. Serial No. 302,006.

To all whom it may concern:

Be it known that I, CHARLES M. LUNGRAN, residing at Bayonne, in the county of Hudson and State of New Jersey, have invented 5 certain new and useful Improvements in Strainers and Perforate Discharges for Lamps, of which the following is a full, clear, and exact description, such as will enable others skilled in the art to which it appertains to 10 make and use the same.

This invention broadly relates to gas-burning apparatus, but more particularly it concerns improvements in that species thereof commonly designated as "mantle lamps". 15 However, as it is applicable with many eminent characteristic advantages to mantle lamps of the inverted type, it will be conducive to clearness to disclose the invention through its embodiment in such connection. 20 In apparatus of this character, particularly when employed under conditions in which considerable dust or other foreign matter pervades the air, as in connection with railroad service, much difficulty has been experienced in keeping the injector nozzle in perfect order and free from the foreign matter which tends to rapidly accumulate in the ori- 25 fice of the nozzle and clog the flow of gas therethrough. The trouble arising from this 30 defect in prior devices of this nature is especially annoying in systems in which a relatively high gas pressure is adopted, since the nozzle aperture takes the form of a fine bore, which, accordingly, may be very easily ob- 35 structed to a serious extent by the fine grit or cinders invariably suspended in the air present in ordinary railroad cars. The cleaning of such obstructed nozzles is at best a delicate opera- 40 tion which, unless skilfully carried out, may result in such alterations in the shape of the bore that the effectiveness of the injector action will be greatly diminished.

This invention, accordingly, has in view, among other objects, the provision of a 45 simple and inexpensive expedient designed to overcome the foregoing defects, whereby the objectionable foreign matter will be completely excluded from the injector nozzle and the operation of the latter enhanced.

50 A further object within the purpose of this invention consists in an improved means of supplying the requisite amount of air to the gases, whereby a highly efficient carburized burning mixture is produced.

55 A further object consists in effecting an ar-

rangement of parts whereby the admission of fresh air to the injector will be insured and whereby the products of combustion will be discharged at a proper point.

A further object of this invention is to so 60 devise and arrange the various parts going to make up the complete structure that access may conveniently be had to the various essentially operative features of the same, in order that they may be cleaned or repaired, 65 as occasion may demand.

Another object is to provide a gas-illuminating apparatus which, from an operative standpoint, will possess a high degree of efficiency and durability in usage, and which, 70 structurally considered, will be of the utmost simplicity consonant with the ends to be attained, being composed of but few parts, all adapted for being made at a minimum of cost and individually so formed as to be capable 75 of being easily assembled into a neat and compact arrangement for accomplishing the purposes intended.

Other objects and advantages will be in part obvious and in part pointed out herein- 80 after.

With these and other ends in view, this invention accordingly consists in the features of construction, combinations of parts, and arrangement of elements which will be ex- 85 exemplified in the embodiment thereof herein- after described and the scope of the applica- tion of which will be indicated in the follow- ing claims.

In order that the invention may be more 90 fully understood and made comprehensible to others skilled in its relating arts, drawings illustrating a convenient manner of carrying out the same are appended as a part of this specification, and, while the controlling prin- 95 ciples of the invention may be otherwise applied by modifications falling within the scope of the claims, the herein disclosed em- bodiment is that which will ordinarily be preferable to employ in practice, and is re- 100 garded as representing substantial improve- ments over the many implied and obvious variations of the same.

The drawing illustrates in sectional eleva- 105 tion the assembled details of the herein de- scribed embodiment of my invention as ar- ranged ready for use, and in such drawing, like numerals of reference refer to corre- sponding parts throughout.

In commercially carrying out this inven- 110

tion, it will be understood that it may be applicable to various types of lamps according to the practical dictates of particular circumstances, but the herein disclosed type of inverted lamps will, in most instances, be found to be well fitted for use in conjunction with the invention. In such form, the lamps may be suspended from a suitable bracket, which may depend directly from a ceiling, or, as shown in the drawing, may extend from a side wall of the car or other inclosure within which the device is to be used. Thus, 1 refers to a wall-plate of such nature as will ordinarily be employed, and extending therefrom is a suitable cock 2 provided with an orifice 3 for the passage of the gas. A suitably-shaped conduit 4 extends from the other end of the cock and terminates at its upper end in connection with a member of the lamp by means of a convenient part which, preferably, constitutes a nipple 5 having a reduced upper end, which is in screw-threaded engagement with the end 6 of conduit 4 and affords a suitable end shoulder for limiting the extent of telescoping of such parts with one another. Such nipple may conveniently be provided in its upper reduced end with a bore 7, which enlarges toward the other end and forms a chamber constituting a feature of a suitable strainer means. Such nipple, in its preferred form, provides intermediate its ends a cylindrical portion 9 with peripheral screw-threads which engage with a locknut 10, and at its lower end such nipple is conically reduced and is provided with peripheral threads 11. This conical end takes into a corresponding seat in the upper end of a part 12 and, because of the said conical arrangement, the 40 nipple is adapted for being readily brought into a perfect fluid-tight union with said part and may be permanently locked in place through the operation of locknut 10 which engages with the upper end of said part. At 45 its lower end, said part is reduced in diameter and at the extreme end of said reduced portion is provided with peripheral threads, as indicated by 13, while the intermediate portion, indicated by 14, is preferably of 50 smooth contour. The purpose of this construction is to enable the said part to be brought into a screw-threaded relation with the lamp body portion 15 with the adjustable screw 16 carried by the same in contact with 55 the smooth portion, whereby these interfitting elements may be locked together against any undesirable reflex relative movement without effecting any undue injury to the threads, which might otherwise result. It 60 will be noted that, because of the reduced end, a shouldered abutment 17 is afforded, and this prevents the telescoping of the two mentioned parts to an excessive extent. As a consequence of the foregoing arrangement 65 of parts, an extension member is formed

which is well adapted for being adjustably positioned with respect to the body portion. This member is designed so that gas passing through the same will undergo an abrupt turn and project any foreign matter suspended therein against a wall of the collection chamber. The preferred arrangement for carrying out this purifying operation is the following: The lower reduced end of the said part 12 is provided with a reduced bore 18, 75 and screw-threaded into or otherwise in communication with such bore is a strainer conduit 19 of tubular form, which extends centrally into the collection chamber, terminating above the bottom thereof, and is open 80 only at its upper end by means of a series of side apertures 20, the area of which may be regulated through the adjustment of a screw 21, which also serves as a closure for the upper end of said strainer tube. At its lower 85 end and within its bore, one or more fine-mesh sieves may also be provided to insure a perfect diffusion and act as a safeguard against the further travel of any foreign matter not deposited in the collection chamber, 90 if it is so desired. It will be noted that such strainer conduit is of somewhat less diameter than the collection chamber, and as a consequence, the through-flowing gas will take a course such that the foreign matter will be 95 deposited in the lower end 23 which serves as a dust receptacle. The nozzle 24 is provided with the usual fine aperture and is peripherally screw-threaded to the lower end of member 12 and thereby made adjustable with respect to said member, so that a precise relationship may be had with the air-inlet, thus 100 securing proper injecting action.

The body portion 15 of the lamp provides one or more laterally extending conduits 105 having apertures 26 for the admission of air, and, intermediate the extreme ends of such laterally-extending conduits and the central portion, one or more suitable air-escape vents will usually be provided, indicated by the 110 dotted lines 27, for conveying away the vitiated products of combustion and discharging the same at a distance from the air inlets, as will be more fully described hereinafter.

The burner nozzle 28 is here shown in 115 screw-threaded attachment to the lamp body 15, but it will be understood that any other form or arrangement of the nozzle, as well as of the parts, may be employed as occasion may make requisite, but that shown 120 is regarded as the preferred form and is generally used in practice in connection with the further details of the lamp.

The shown supporting means for the mantle, globe and shade conforms to the invention disclosed in the co-pending application, Serial No. 302,426, filed February 23rd, 1906, and, accordingly, need not be here specifically described. It will be noted, however, that this disclosure exemplifies a specific 130

manner of utilizing the said means not shown in the cited application, in that a different and more beneficial circulation of air and products of combustion is obtained.

5 An important feature provided by this invention resides in the arrangement and form of the parts whereby fresh air is caused to mix with the products of combustion prior to or during their escape upward and through 10 the discharge conduit. To this end, the discharge conduit means is perforated at suitable points, and preferably such perforations will be arranged so that the intaking fresh air will flow along the desired course without 15 impeding in any way the discharge of the products of combustion. The shown embodiment is well adapted to carry out the desired circulation, and to that end, the same provides an air inlet passage 33 leading from 20 the exterior of globe 34, which acts as a deflector and conduit for the passage of the products of combustion. The latter follow the course of arrows 35 and flow directly upward and through the channels 27 in the 25 manner indicated by arrows 36. This not only prevents any undue heating of the parts, but materially improves the action of the lamp and, by increasing the volume of the discharged gases, renders the flow thereof 30 more certain and uniform. Actual practice has established the fact that a lamp constructed in this manner will also be less heated in the more distant features and is consequently less liable to become tarnished or 35 objectionably affect the finish of adjacent woodwork. Furthermore, the discharged vitiated products are less heated and the danger of setting fire to adjacent parts is practically eliminated. Other obvious ad- 40 vantages accrue to the arrangement. While the inlet passage 33 may be provided for in various structural ways, the shown exemplification is regarded as possessing peculiar advantages in that all the advantages of the 45 other shown structural features may be fully preserved to the lamp. In this form the support 37 will be spaced a distance from the bottom of the lamp body 25, either by adjustably screwing such support upon the 50 burner nozzle or by providing suitable lugs or stops 38 adapted to space the support from the lamp body.

A further feature of this invention lies also in the ventilator or deflecting member which 55 may consist of hollow shells 29 and 30, which are perforate at top and bottom, and also intermediate, if desired, and may be given any desired ornamental configuration for the sake of effect. Such parts interfit along 60 matching faces 31 and, at their extreme ends, abut with the lamp body and aforesaid dust removing member respectively, and are thereby firmly retained in place.

The operation of the device may now be 65 briefly explained.

The gas enters originally from the conduit 4 and passes into the chamber 8 at the upper end thereof and at first flows at a high velocity in a downward direction and ultimately turns and finally escapes into the 70 strainer tube 19 through the lateral orifices 20 at the upper end thereof. It will be clear that, while the gas, which is of little mass, is capable of being abruptly checked in its flow, solid foreign matter, because of its 75 greater mass, will be projected toward the latter and will lodge in chamber 23, being restrained against escape by the various side-walls. The gas, however, is free to outflow through the strainer, being ultimately ejected 80 from the orifice of the nozzle 24 in a stream which flows by the inner mouth of the air-inlet nozzle 26 through which a sufficient amount of fresh air will be supplied and subsequently diffused with the gas to form a 85 homogeneous mixture suitable for combustion adjacent the mantle. The products of such combustion, because of their heated condition, rapidly rise and, passing through the channels indicated by dotted lines 27, 90 ultimately escape through the openings in the upper portion of the member 30. It will be also noted that, in actual service, the parts tend to become somewhat heated, and this also aids in maintaining the desired cir- 95 100 culation, and, as a consequence, fresh air will be continually drawn through the lower openings 33 and by the mouth of the inlet openings 26, through which, therefore, only fresh air may be drawn.

It will now be apparent that this invention is one well adapted to attain the above-enumerated objects and advantages. It is an essentially practical device and is specially adapted for hard usage in connection 105 with railroad service and, moreover, it admits a construction such that the foreign matter suspended in the gas will be excluded from contact with the nozzle, and, therefore, the latter may be used throughout long periods without becoming impaired or disarranged. Furthermore, the arrangement is such that the products of combustion are discharged at a distance from the inlet orifice of the air supply, and thus the 110 combustion may take place in a perfect manner without any undesirable dilution of the carburized gases.

Having described my invention, what I claim as new and desire to secure by Letters 120 Patent, is:—

1. A device of the nature disclosed comprising in combination, a lamp-body having a depending burner-nozzle, a hollow shell encompassing the upper part of said lamp-body for receiving the products of combustion rising from said burner-nozzle, said shell having in its lower portion perforations for enabling relatively cool air to enter said shell and intermingle with said rising prod- 125 130

- ucts prior to their ultimate discharge from said shell, and an inspirator having one or more laterally extending air inlets terminating within said shell below the region in 5 which said products are received by said shell.
2. A device of the nature disclosed comprising in combination, a lamp-body having a depending burner-nozzle, a hollow shell 10 encompassing the upper part of said lamp-body for receiving the products of combustion rising from said burner-nozzle, said shell having in its lower portion perforations for enabling relatively cool air to enter said 15 shell and intermingle with said rising products prior to their ultimate discharge from said shell, and an inspirator having one or more laterally extending air inlets terminating within said shell remote from the path of the 20 products escaping through said shell.
3. A device of the nature disclosed comprising in combination, a lamp-body having a depending burner-nozzle, a hollow shell 25 encompassing the upper part of said lamp-body for receiving the products of combustion rising from said burner-nozzle, said shell having in its lower portion perforations for enabling relatively cool air to enter said shell to commingle with said rising products prior 30 to their ultimate discharge from said shell, an inspirator arranged in said lamp-body and having one or more laterally extending air inlets arranged adjacent the lower end of said 35 perforate shell, upwardly extending channels for conveying products of combustion past said air inlets to prevent contamination of the intaken fresh air by said products, and a globe support secured to said lamp-body and having perforations enabling air to inter- 40 mingle with the rising products of combustion prior to their passage through said channels.
4. A device of the nature disclosed comprising in combination, a lamp-body having 45 a depending burner-nozzle, a hollow shell encompassing the upper part of said lamp-body for receiving the products of combustion rising from said burner-nozzle, said shell having in its upper portion perforations for 50 enabling said products to escape from said shell and an inspirator having one or more laterally extending air inlets terminating adjacent the lower end of said perforate shell.
5. A device of the nature disclosed comprising in combination, a lamp-body having 55 a depending burner-nozzle, a hollow shell encompassing the upper part of said lamp-body for receiving the products of combustion rising from said burner-nozzle, said shell 60 having in its upper portion perforations for enabling said products to escape from said shell, and an inspirator having one or more laterally extending air inlets terminating within said shell below the region in which 65 said products are received by said shell.
6. A device of the nature disclosed comprising in combination, a lamp-body having a depending burner-nozzle, a hollow shell encompassing the upper part of said lamp-body for receiving the products of combustion rising from said burner-nozzle, said shell having in its upper portion perforations for enabling said products to escape from said shell, and an inspirator having one or more laterally extending air inlets terminating within said shell remote from the path of the products escaping through said shell. 70
7. A device of the nature disclosed comprising in combination, a lamp-body having a depending burner-nozzle, a hollow shell 75 encompassing the upper part of said lamp-body for receiving the products of combustion rising from said burner-nozzle, said shell having in its upper portion perforations for enabling said products to escape from said shell, and an inspirator arranged in said lamp-body and having one or more laterally extending air inlets arranged adjacent the lower end of said perforate shell, said lamp-body providing an upwardly extending 80 channel for conveying products of combustion past said air inlets to prevent contamination of the intaken fresh air by said products, and a globe support secured to said lamp-body and having perforations enabling air 85 to intermingle with the rising products of combustion prior to their passage through said channels. 90
8. A device of the nature disclosed comprising in combination, a lamp-body having a depending burner-nozzle, a hollow shell 95 encompassing the upper part of said lamp-body for receiving the products of combustion rising from said burner-nozzle, said shell having in its upper portion perforations enabling the products of combustion to escape and having in its lower portion perforations for enabling relatively cool air to enter said shell and intermingle with said rising products prior to their ultimate discharge from 100 said shell, and an inspirator having one or more laterally extending air inlets terminating within said shell below the region in which said products are received by said shell. 105
9. A device of the nature disclosed comprising in combination, a lamp-body having a depending burner-nozzle, a hollow shell 110 encompassing the upper part of said lamp-body for receiving the products of combustion rising from said burner-nozzle, said shell having in its upper portion perforations enabling the products of combustion to escape and having in its lower portion perforations for enabling relatively cool air to enter said shell and intermingle with said rising products prior to their ultimate discharge from said shell, and an inspirator having one or more laterally extending air inlets terminating within said shell remote 115
- 120
- 125
- 130

- from the path of the products escaping through said shell.
10. A device of the nature disclosed comprising in combination, a lamp-body having a depending burner-nozzle, a hollow shell encompassing the upper part of said lamp-body for receiving the products of combustion rising from said burner-nozzle, said shell having in its upper portion perforations enabling the products of combustion to be discharged and having in its lower portion perforations for enabling relatively cool air to enter said shell and commingle with said rising products prior to their ultimate discharge from said shell, an inspirator arranged in said lamp-body and having one or more laterally extending air inlets arranged adjacent the lower end of said perforate shell, said lamp-body providing an upwardly extending channel for conveying the products of combustion past said air inlets to prevent contamination of the intaken fresh air by said products, and a globe support secured to said lamp-body and having perforations enabling air to intermingle with the rising products of combustion prior to their passage through said channels.
11. A device of the nature disclosed comprising in combination, an elongated vertically arranged lamp-body adapted to receive gas at its upper end and to discharge said gas mixed with air at its lower end, an inspirator arranged in said lamp-body intermediate the upper and lower ends thereof, one or more air tubes extending laterally from the nipple of said inspirator and terminating a short distance from the vertical axis of said lamp-body, an incandescing device arranged adjacent the lower end of said lamp-body, said lamp-body providing a channel for the escape of the products of combustion, said channel extending upwardly between the outer terminals of said air tubes and said lamp-body, and a reticulated shell encompassing said lamp-body above said air tubes and adapted to receive and convey upwardly the products of combustion discharged by said channel.
12. A device of the nature disclosed comprising in combination, a burner having a mixing chamber and a nozzle depending therefrom, said burner providing air inlets opening within a deflecting means and leading laterally to said chamber and providing upright escape channels opening above and below said inlets, and a deflecting means extending below the end of said nozzle and adapted to direct the products of combustion toward the lower ends of said escape channels whereby they may traverse and be discharged above said inlets, said deflecting means being spaced a distance from said burner, whereby fresh air may be conveyed into and from said vents to cool the same and facilitate the discharge of said products 65 therefrom.
13. In a device of the class described, a member consisting of a plurality of telescoping sections constituting the inclosing walls of a chamber, said member providing an inlet orifice adjacent the upper end of said chamber, and an outlet orifice above the bottom thereof, whereby gases may flow through said chamber and deposit foreign matter therein.
14. In a device of the class described, a member consisting of a plurality of detachable telescoping sections forming the inclosing walls of a collection chamber, said member having an inlet orifice leading into the upper end of said chamber and arranged to deliver a stream of gas toward the bottom thereof, and having an outlet orifice above said bottom whereby gas may outflow after depositing the foreign matter intermingled 75 80 85 therewith.
15. In a device of the class described, a member consisting of a plurality of telescoping sections having conical contacting faces and forming the inclosing walls of a collection chamber, said member providing a substantially vertical inlet orifice leading into the upper end of said chamber, whereby gas may be delivered under considerable velocity into said chamber and toward the bottom 90 95 thereof to deposit foreign matter thereon, and having transverse escape orifices above said bottom whereby the purified gas may flow from said chamber.
16. In a device of the class described, a member consisting of a plurality of detachable, telescoping sections in fluid-tight union along conical, threaded peripheries, said sections constituting inclosing walls of a collection chamber, and means whereby gas flow- 100 105 ing through said chamber will follow a tortuous course and deposit foreign matter therein.
17. In a device of the class described, a member consisting of a plurality of telescoping sections constituting the inclosing walls of a chamber, the one section providing an inlet orifice adjacent the upper end of said chamber, and a conduit extending from the other section and terminating adjacent the 110 115 upper end of said chamber and provided near its termination with an aperture in communication with said chamber, whereby gas may outflow therefrom after depositing the foreign matter intermingled therewith.
18. In a device of the class described, a member consisting of a plurality of telescoping sections having conical contacting faces and constituting the inclosing walls of a collection chamber, one of said sections providing a substantially vertical inlet orifice leading into the upper end of said chamber, whereby 120 125 gas may be delivered under considerable

velocity into said chamber and toward the bottom thereof to deposit foreign matter thereon, and a conduit rising from the section constituting the bottom wall of said 5 chamber and terminating adjacent the aforesaid inlet orifice, whereby the purified gas may outflow from said chamber through the upper end of said conduit.

19. In a device of the class described, a 10 member consisting of detachable, telescoping sections in fluid-tight union along conical, threaded faces, said sections constituting the inclosing walls of a collection chamber, one of said sections providing a substantially 15 vertical inlet orifice leading into the upper end of said chamber, whereby gas may be delivered under considerable velocity into said chamber and toward the bottom thereof to deposit foreign matter thereon, and a conduit 20 extending from the other section and terminating adjacent the upper end of said chamber and provided near its termination with a laterally extending aperture establishing communication with said chamber 25 whereby gas may outflow therefrom after depositing the foreign matter intermingled therewith.

20. In a device of the class described, a member having a collection chamber provided 30 with conduits leading thereto and therefrom and arranged to compel gases to abruptly turn when passing through said chamber and deposit solid foreign matter therein, an injector nozzle in communication 35 with the conduit leading from said chamber, and one or more air conduits transversely leading toward the end of said nozzle, and a perforate inclosing shell encompassing 40 said parts and adapted to admit fresh air through its lower end and discharge the viti- ated products of combustion through its upper end.

21. In a device of the class described, a member having an internal collection chamber 45 provided at its upper end with a vertical inlet orifice and having an escape orifice at said end transversely leading from said chamber, whereby gases will abruptly turn and deposit solid matter in flowing through 50 said chamber, a nozzle in communication with said escape orifice, one or more air conduits transversely leading to the end of said nozzle, and a shell encompassing the aforesaid parts and provided with top and bottom 55 perforations for the escape of contaminated and the admission of fresh air respectively.

22. In a device of the class described, a 60 burner having a mixing chamber and terminating in a nozzle, and a conduit extending below the lower end of said nozzle and arranged to receive and discharge the products of combustion therefrom, said conduit having one or more lateral openings adapted to introduce air and diffuse the same with said 65 products, said burner providing air inlet

passages opening opposite certain of said openings below the point of discharge of said products whereby fresh air may be conveyed to said mixing chamber.

23. In a device of the class described, a 70 burner having a mixing chamber and terminating in a downwardly extending nozzle, and a conduit extending below said nozzle and adapted to receive the products of combustion therefrom and discharge the same at 75 its upper end, said conduit providing one or more lateral openings adapted to introduce fresh air into said conduit and thereby cool the same, said burner having an air inlet opening opposite certain of said openings 80 below the discharge end of said conduit and leading into said mixing chamber, whereby fresh air uncontaminated by products of combustion may be conveyed thereto.

24. In a device of the class described, a 85 burner having a mixing chamber, transverse inlets leading thereto, said burner providing vents adapted to receive the products of combustion and discharge the same above said inlets, and a perforate ventilator encompassing said burner and adapted to receive and discharge the said products of combustion and simultaneously direct fresh air toward said inlets.

25. In a device of the class described, a 95 burner nozzle having an air inlet, means for conducting the products of combustion therefrom, said means being provided with lateral openings adapted to diffuse relatively cool air with said products prior to their discharge 100 from said means, and a perforate inclosure arranged to receive said mixture and discharge the same at a distance from said air inlet.

26. In a device of the class described, a 105 burner having a mixing chamber and terminating in a nozzle, a conduit extending below the lower end of said nozzle and arranged to receive and discharge the products of combustion therefrom, said conduit having one or more lateral openings adapted to introduce air and diffuse the same with said 110 products, said burner providing inlet passages opening below the point of discharge of said products whereby fresh air may be 115 conveyed to said mixing chamber, and an inclosure having top and bottom openings whereby the said products may discharge through the top and fresh air be drawn through the bottom and directed toward 120 said inlets.

27. In a device of the class described, a 125 burner having a mixing chamber and terminating in a downwardly extending nozzle, a conduit extending below said nozzle and adapted to receive the products of combustion therefrom and discharge the same at its upper end, said conduit providing a lateral perforation adapted to introduce fresh air into said conduit and thereby cool the same, 130

said burner having an inlet opening below the discharge end of said conduit and leading into said mixing chamber, whereby fresh air uncontaminated by products of combustion may be conveyed thereto, and an inclosure having top and bottom openings, whereby the said products may escape through the top and fresh air may be drawn through the bottom and directed toward said inlets.

28. In a device of the class described, a burner having a mixing chamber, a nozzle depending therefrom, said burner providing inlets leading laterally to said chamber and providing transverse discharge vent openings above said inlets, and a deflecting means extending below the end of said nozzle and adapted to convey the products of combustion therefrom toward the lower ends of said vents, said deflecting means being spaced at a distance from said burner, whereby fresh air may be conveyed into and from said vents to cool the same and facilitate the discharge of said products therefrom, and a perforate inclosure arranged to receive and discharge said products above said inlets and adapted to supply said inlets with fresh air.

29. In a device of the class described, a burner, means for internally supplying the same with fresh air, means providing diverse channels adapted respectively to convey products of combustion from said burner, intermingle the same with fresh air and ultimately discharge the said mixture at a distance from the inlet of the aforesaid means, and a perforate inclosure for said parts.

30. In a device of the class described, a burner having a mixing chamber, and transverse inlets leading thereto, said burner providing vertically extending vents through the body thereof adapted to receive and discharge the products of combustion above said inlets, and a perforate ventilator encompassing said burner and adapted to receive and discharge the said products of combustion and simultaneously direct fresh air toward said inlets.

In testimony whereof I affix my signature, in the presence of two witnesses.

CHARLES M. LUNGREN.
